UNITED STATES PATENT OFFICE.

WILLIAM L. HOOVER, OF NORWAY, IOWA.

STRAP SPLICE OR CLASP.

SPECIFICATION forming part of Letters Patent No. 257,945, dated May 16, 1882.

Application filed March 16, 1882. (Model.)

To all whom it may concern:

Be it known that I, WILLIAM L. HOOVER, a citizen of the United States, residing at Norway, in the county of Benton and State of Iowa, have invented certain new and useful Improvements in Strap Splice or Clasp; and I do hereby declare the following to be a full, clear, and exact description of the invention, such as will enable others skilled in the art to 5

io which it appertains to make and use the same.

This invention has relation to means for splicing or looping harness-straps; and the object of the improvement is to provide a strap-splice which may be applied in any case where 15

15 a strap breaks, or which may be used for all purposes where a sewed, riveted, or cemented splice is used about harness or in forming a loop in the harness.

My invention therefore consists in a metal- 20

lic plate of suitable width and length, and provided with an elongated button-slot in one end and a button or locking-stud in the other, as hereinafter set forth.

My invention further consists in a metallic 25

casing, of suitable length and breadth, formed or provided with an elongated button-slot in one end and a button-stud in the other, in combination with a metallic cover fitting the walls of the casing and formed or provided 30

30 with an elongated button-slot in one end and a button-stud in the other, as hereinafter set forth.

In the accompanying drawings, forming a 35

part of this specification, Figure 1 is a perspective view, showing my improvements on a looped strap. Fig. 2 is a similar view, showing the same applied to spliced straps. Fig. 3 is a longitudinal sectional view of Fig. 1, and Fig. 4 is a perspective view of the casing 40

40 and cap-plate.

In the annexed drawings, the letter A represents a metallic casing, which is struck up or cast of any desired dimensions, and therein formed the elongated button-slot *a* in one 45

end thereof, and in the other end fixed by riveting or other means in the button or locking stud *b*. This button-stud *b* projects sufficiently above the line of the walls of the casing to receive the clasping-plate below the flange of 50

the button, and the neck is choked, or formed

55 with an annular groove fitting the elongation of the slot beyond the eye which receives the button.

The letter B represents the top plate or cover, 55 also formed with an elongated slot, *c*, and pro-

vided with a stud, *d*, similar in all respects to that formed and fixed in the casing. This slot *c* and stud *d* of the cover register respectively with the stud *b* and slot *a* of the casing, so that when the parts are united they are 60 held together by the necks or shouldered portions of the buttons slipping in the elongated portions of the slots and securing the pieces together.

To apply my improved splice to a strap, a 65

hole is cut in the strap for the insertion of the stud of the casing, and at the proper distance from the hole an elongated slot is made, corresponding as near as may be with the elongated slot in the casing. The end of the piece 70

to be spliced on is then prepared in the same way to receive the stud of the cover or clamp, except that the order of perforations is reversed. The ends of the straps are then fixed in the casing with the stud through them, 75

and the stud of the cap or cover is then put through the unoccupied holes, the stud of the casing through the slot in the cap, and the cap then forced under the button, which also 80

forces the button on the casing side into the elongation of the slot, and thus the splice is 85

complete, and the parts securely and strongly held together. The mode of forming a loop in a strap is somewhat similar, as seen in Fig. 1 of the drawings.

I reserve the right to vary the construction and arrangement of parts without departing from the spirit of the invention.

What I claim as my invention, and desire to 90

secure by Letters Patent, is—

1. In a means for splicing harness or similar straps, a metallic plate formed with a longitudinal elongated button-slot in one end and a fixed button or locking stud in the other end adapted to co-operate with a similarly- 95

constructed plate, substantially as set forth.

2. A metallic casing, A, formed with side 100

walls and provided with an elongated button-slot in one end and a button-stud in the other end, in combination with a metallic plate, B, serving as a clasping means, formed with a longitudinal elongated button-slot in one end and a fixed button-stud in the other end, substantially as described.

In testimony whereof I have affixed my sig- 105

nature in presence of two witnesses.

WILLIAM L. HOOVER.
